SCREEN ATTACHMENT FOR WINDOWS

Henry N. Renton, Germantown, Pa., assignor to
 Hunter Manufacturing Corporation, Bristol,
 Pa., a corporation of Delaware

Application September 2, 1949, Serial No. 113,877

8 Claims. (Cl. 160—100)

1

This invention relates to screen attachments for windows. More specifically, it is concerned with screen attachments for sliding sash windows of a type wherein a screen sheet is connected at one end to a sash and its other end connected to a roll rotatively supported on the frame of the window.

My invention is directed toward the provision of a window screen attachment of the kind referred to which is self rolling; which is simple in construction and reliable in operation; which lends itself readily to economic production in quantity; which is easily and quickly applied to or removed from existent windows; and which, moreover, is sturdy against disarrangement in use.

Other objects and attendant advantages will appear from the following detailed description of the attached drawings, wherein—

Fig. 1 is a broken out view in elevation of a window with a screen attachment conveniently embodying my invention as it appears from within doors, the screen being shown in extended or operative position.

Fig. 2 is a vertical section of the organization taken as indicated by the angled arrows II—II in Fig. 1.

Fig. 3 is a fragmentary view in vertical section taken as indicated by the angled arrows III—III in Fig. 1, showing the screen withdrawn.

Figs. 4 and 5 are fragmentary views on horizontal section taken as indicated respectively by the angled arrows IV—IV and V—V in Fig. 1.

Fig. 6 is a transverse section through one edge of the rollable screen sheet of the attachment, taken as indicated by the angled arrows VI—VI in Fig. 1 and drawn to a larger scale.

Fig. 7 shows a fragment of an alternative form of screen material which may be used in place of the screen sheet shown in Figs. 1—5.

Fig. 8 is a fragmentary view in transverse section taken as indicated by the angled arrows VIII—VIII in Fig. 7.

Figs. 9, 10 and 11, 12 are views like Figs. 7, 8 showing other alternate forms of screen material suitable for use in connection with the attachment.

The window structure herein illustrated for convenience of exemplifying my improved screen attachment, is of the double hung auxiliary or

2

storm type constructed of sheet metal with upper and lower sashes 15 and 16. As shown, the sashes 16, 15 are confined to slide within a frame of which the opposite side bars 17 and the top and bottom bars 18 and 19 are rigidly united. This rigid frame is held in place by an adapter frame whereof the opposite side bars 20 and the top and bottom bars 21 and 22 are made to channel section to fit over the corresponding bars of said rigid frame, and engage telescopically into upper and lower corner pieces 24 and 25. The adapter frame is thus adjustable for snug fit into the opening 26 of the frame 27 of a permanent window of a building, with interposition of plastic sealing material as at 28 all around, backed against the shutter stop 29 of said permanent frame. The adapter frame is secured by screws such as shown at 30 in Fig. 4, passed at suitable intervals through its component bars and 10 engaged into the shutter stop 29. The side edges of the lower sash 16 are longitudinally grooved, as at 32 in Figs. 3 and 4, to engage with guide strips 33 recessed into the side bars 17 of the rigid frame. It will be noted from Fig. 1 that 15 the guide strips 33 extend up from the bottom bar 19 of the rigid frame 17 and that their length is somewhat less than half the height of the window, as a consequence of which the lower sash 16 can be removed from within doors for convenience of cleaning after the manner disclosed in Patent No. 2,329,485, granted to me on September 14, 1943. Clamp devices (not shown), operable by thumb nuts indicated at 34 in Figs. 1 and 3, serve as a means for holding the lower sash against shifting in different raised positions.

The screen attachment with which the present invention is more especially concerned, comprises a roll 35 which is enclosed in a housing 36 of sheet metal adapted to be supported on the 20 sill 37 of the permanent window frame 27. As shown, the housing 36 has a top wall, a back wall, and end walls which latter are provided with horizontal slots 38 for the journalling of end trunnions 39 on the roll 35, and of which the 25 lower edges are sloped to correspond with the outward declination of the sill top 37. The end walls of the housing 36 are extended downwardly and inwardly as shown in Fig. 1 to provide short horizontal tongues 40, which, incident to application of the housing to the window, are engaged

3

beneath oppositely-directed hold-down tongues 41 nailed or screwed to the top of the sill 37. Riveted to the bottoms of the tongues 40 adjacent the front of the housing 36 are rearwardly directed spring elements 42 which are biased downwardly and provided with spurs 43 to engage into the top of the sill 37. The spring elements 42 are extended upwardly of the back of the housing 36 and terminate in finger lift curls 44. By the means just described, the housing 36 is held against displacement on the window sill with a longitudinal bar 45 at the front and adjacent the top thereof abutted against the lower corner pieces 25 of the adapter frame.

Connected at one end to the roll 35 by an embracing spring clip 50, see Fig. 3, is a flexible screen sheet 51 consisting of a web of mesh fabric 52 to one face of which are secured, along opposite side edges, strips 53 of spring metal which are inherently self coiling and thus tend to induce rotation of the roll 35 to wind the screen sheet into a compact coil, with the several turns or convolutions of the latter in direct mutual contact as shown in Fig. 3. The screen sheet 51 is passed upward through a slot 55 formed between the inner edge of the top of housing 36 and the bar 45, and its transverse distal edge is wrapped about a rod 56 and clamped within the longitudinal recess 57 of a terminal strip 58. As shown, the terminal strip 58 is fashioned from sheet material with a horizontal clip flange 59 at the top adapted to frictionally engage, with capacity for detachment, over the outwardly projecting flange 60 of an angle strip 61 affixed to the inside face of the bottom rail of the lower sash 16. For guidance of the screen 51, I have provided channels 62 at the opposite sides of the window to receive the spring strips 53 at the screen edges. As shown in Fig. 5, the inner flanges 63 of the channels 62 are extended laterally to reach inward between the side bars 17 of the rigid frame and the contiguous longitudinal flanges of the side bars 20 of the adapter frame. Registering spot indentations, shown at 65 in Fig. 5, are relied upon to hold the guides 62 against displacement in assembly.

As the sash 16 is raised, the screen sheet 51, by virtue of the attachment to said sash, is drawn from the roll 35 through the slot 55 at the top of the housing 36 against the resistance of the spring strips 53 which are constrained to travel in straight paths by the guides 62, with the mesh 52 spanned perfectly flat between them. When raised to the desired height, the sash 16 is secured by tightening thumb nuts 34. As the sash 16 is lowered, the roll 35 is rotated by the self coiling action of the spring strips 53 and the screen 51 collected thereon in the form of a compact mass as shown in Fig. 3. Incident to the operation of the screen 51, the roll 36 will shift its position to compensate for change in the diameter of the screen coil as the latter decreases or increases in size, since the roll trunnions 39 are free to move transversely within the slots 38 in the ends of the housing 35. Smooth travel of the screen through the slot 55 and of its strip reinforced side edges in the guides 62 is in this way preassured.

To prevent the sash 16 from falling out of the frame when fully raised with the screen attached, I have further provided, in accordance with my invention, auxiliary guards which are shown at 67 in Figs. 1, 2 and 4. These guards have the form of vertically-arranged spring tongues which are curved outwardly top and bottom to facilitate

4

entry and retirement of the top edge of the sash beneath and from beneath them, and which are formed with lateral shanks 68 to engage, like the flanges of the guides 62, between the side bars 17 of the fixed frame and the overlap flanges of the side bars 20 of the adapter frame, and to be held in assembly by interengaging spot indentations as at 69 in Fig. 4. It is to be understood that the guards 67 are disposed at an elevation well above the tops of the sash guides 33 to permit upward and inward removal of the sash in the manner hereinbefore stated.

The mesh fabric 51 may be woven from textile yarn or from metallic wire as desired, and the 15 spring strips secured to them with cement as conventionally indicated at 10, or they may be secured by rivets 71 at lengthwise intervals as shown in Figs. 7 and 8. As an alternative, the 20 spring strips may be interwoven with the mesh fabric slightly inward of its side edges after the manner illustrated in Figs. 9 and 10 or as shown in Figs. 11 and 12, instead of wide strips, several 25 narrower spring strips 53a may be interwoven in closely spaced relation adjacent each side edge 30 of the mesh fabric. These various types of screen material illustrated and the method of producing them have been made subjects of a separate 35 patent application, Serial No. 114,809, filed by me also concurrently herewith.

30 My improved screen attachment is not necessarily restricted in its use to the lower sash of the illustrated window, since it can be adapted as readily for use with the upper sash, in which case the roll housing will be secured to the top 35 cross member of the permanent window and the distal edge of the screen sheet attached to the top bar of said upper sash. Moreover, through suitable modifications within the scope of the appended claims, the attachment can be adapted 40 for use in connection with the sashes of permanent windows in climates where auxiliary or storm windows are not desired or necessary.

Having thus described my invention, I claim:

1. A window screen comprising a sheet of mesh fabric with strands of self coiling spring metal affixed along its opposite side edges, one end of the sheet adapted to be secured to a roll freely rotatably supported in a fixed portion of the window, and means at the other end of the sheet for detachably securing the sheet to a cross rail of a sliding sash of the window.

2. A window screen according to claim 1, wherein the self coiling spring strands are of flat strip metal and secured to one face of the mesh fabric at lengthwise intervals by riveting.

3. A window screen according to claim 1, wherein the mesh fabric is of non-metallic material; and wherein the self coiling spring strands are of flat strip metal cemented to one face of the fabric along its opposite edges.

4. A window screen according to claim 1, wherein the mesh fabric is of metal; and wherein the self coiling spring strands are flat metal strips woven into the fabric at opposite side edges.

5. A window screen according to claim 1, wherein the self coiling spring strands are of flat strip metal and are cemented to the mesh fabric at opposite side edges thereof.

6. A window screen according to claim 1, wherein the self coiling spring strands are of flat strip metal interlaced with the fabric at opposite side edges thereof.

7. A window screen comprising a sheet of mesh fabric with strands of self coiling spring metal 70 affixed along its opposite side edges, one end of

the sheet adapted to be secured to a roll freely rotatably supported in a housing for the screen, and means at the other end of the sheet for detachably securing the sheet to a cross rail of a sliding sash of the window.

8. A window screen comprising a sheet of mesh fabric with strands of self coiling spring metal affixed along its opposite side edges, one end of the sheet adapted to be secured to a roll freely rotatably supported in a fixed portion of the window, and the other end of the sheet having a horizontally disposed clip flange adapted to detachably secure the sheet to a horizontal flange affixed to a sliding sash of the window.
